ATTORNEY

UNITED STATES PATENT OFFICE.

LEVI BERGER, OF PHILADELPHIA, PENNSYLVANIA.

DESIGN FOR A WATER-COOLER HANDLE.

SPECIFICATION forming part of Design No. 12,213, dated April 5, 1881.

Application filed February 19, 1881. Term of patent 7 years.

To all whom it may concern:

Be it known that I, LEVI BERGER, a citizen of the United States, residing at the city of Philadelphia, in the State of Pennsylvania, have invented or produced a new and useful Design for Water-Cooler Handles; and I do hereby declare the following description to be a full, clear, and exact specification of the same, reference being had to the accompanying drawings, forming part of this specification, wherein—

Figure 1 is a front elevation of my design, and Fig. 2 is a side elevation thereof.

My design for handle has a loop or bow, A, of such configuration that in cross-section it shows a diamond or approximate figure, having four ribs or ridges, a , with channels or grooves a' between the same. The upper bar or cross-piece of the loop, A', is also obliquely lined or ridged, as shown at a^2 and a^3 . The pendant B has fluted wings b b and a terminal,

b' , which is approximately of spear-point shape, with fluted edges b^2 . Said pendant has also an intaglio line, b^3 , with branches b^4 at the ends thereof.

25

What I claim as my invention is as follows:

1. The loop-bar A', having oblique ridges a^2 a^3 , substantially as shown and set forth.
2. The pendant B, with fluted wings b b , curved diverging loop-arms, and spear-point terminal b' , substantially as shown and described.

3. The design for a handle, substantially as shown and set forth.

In testimony that I claim the foregoing I have hereunto set my hand this 17th day of February, 1881.

LEVI BERGER.
